UNITED STATES PATENT OFFICE.

THOMAS C. SHEEHAN, OF ESSEX FELLS, NEW JERSEY, ASSIGNOR, BY MESNE ASSIGNMENTS, TO AMERICAN HIGH SPEED PRESS COMPANY, OF NEW YORK, N. Y., A CORPORATION OF NEW YORK.

GRIPPER MECHANISM FOR PRINTING-PRESSES.

1,123,023.

Specification of Letters Patent.

Patented Dec. 29, 1914.

Original application filed August 29, 1906, Serial No. 332,470. Divided and this application filed January 27, 1914. Serial No. 814,672.

To all whom it may concern:

Be it known that I, THOMAS C. SHEEHAN, a citizen of the United States, residing at Essex Fells, in the county of Essex and State 5 of New Jersey, have invented a new and useful Gripper Mechanism for Printing-Presses, of which the following is a specification.

This is a division of my application Serial 10 No. 332,470, filed August 29, 1906, for a printing machine.

The present invention relates particularly to that class of printing machines known as self-feeding automatic platen presses. In 15 order to do high class work in one or more colors on this kind of a press, a smooth and easy gripper motion is demanded. My invention provides for this feature and also for a novel and improved construction and 20 arrangement of parts in such a manner that the noise and vibration incidental to the operation of the machine are reduced, if not entirely absent.

In carrying out my invention, I provide 25 simple but effective gripper mechanism, adapted to travel in a direction parallel to the printing surface of the platen.

Other valuable features, as well as a preferred form of mechanism for carrying out 30 the invention, are disclosed in the following specification and the accompanying drawings, in which like parts are indicated by like reference numerals, and in which—

Figure 1 is a side elevation of a press embodying my invention. Figs. 2 and 3 are 35 side views of the gripper mechanism showing the press in its open and closed positions, respectively. Fig. 4 is a view looking toward the platen, and showing the gripper 40 mechanism. Figs. 5 and 6 are detail views of parts of the latter. Fig. 7 is a view of the side of the registering devices opposite that shown in Fig. 1, and Fig. 8 is a plan of the same.

The reference numeral 1 indicates the side 45 frames of the machine, for suitably supporting the component parts of the same. The said frames are connected in any suitable and convenient manner.

50 2 indicates the main shaft extending transversely of the machine, and to which motion is imparted by means of the gear 3, meshing

with the pinion 4, to which power is applied in any suitable manner.

5 indicates the bed carrying the inking mechanism of well known construction and of which only the outlines are shown. The bed is pivoted in the frame at 6 and oscillates in the well known manner through the instrumentality of the connection 7 and 55 crank 8 carried by the shaft 2 on one side of the machine. In the present instance, there is shown a pneumatic feeding device 9, of usual construction, and to which power is applied by means of the hose 10 and air cylinder 11, whose piston is operated by means of the rod 12, carried by the eccentric ring 13, on the shaft 14, to which motion is applied by means of the gear 15 meshing with the aforesaid pinion 4. The said gear 15 has a 60 crank to transmit motion to the shaft 6 by means of rod 17 and crank 18. Upon said shaft the delivery gripping mechanism is 65 mounted by means of swinging arms 19, only one of which is seen.

70 It is not necessary to go into details of the construction or operation of the above parts, inasmuch as the same are well known, and form no part of the invention.

75 Between the side frames and adjacent to the feed is located the registering table 20, hereinafter called the table, which is supported on and between brackets 21. The brackets are pivoted on a shaft 22, and are adapted to be swung upward, taking the table 80 with them, so as to permit of an unobstructed view of the interior parts of the machine, and to aid in cleaning or when "making ready." Normally the table and brackets are held in position by their 85 weights. Between the brackets and on the table are mounted the various devices for registering the sheets and placing the same in position for the grippers. The tapes, 24, pass over the surface of the table, around 90 rolls 25 and 26. The tapes may be driven in any manner, and carry the sheet from the feed to front registering gages 28. The sheet is carried by the tapes under longitudinal guide bars 30. The front gages 28 are 95 mounted upon a rock shaft 54 which at one side carries a cam roll 55 in engagement with a cam 56. This cam is pivoted on the brackets 21, at 57, and operated by means of 100

a forked connection 58, carrying a cam roll 59, co-acting with a cam 60, on the shaft 22. On the pivot 57 is also pivoted a turning lip 65, which is in one piece with the cam 56 above mentioned, and is provided with projections, as 66, upon which the front gages 28 rest. Between these projections the grippers act to seize the sheets as will appear.

The sheet is fed from the feed 9 on the table, when it travels on top of the tapes, till it reaches the front gages 28. When a sheet has been fed toward the gages 28 and is ready to be acted upon by the grippers, the turning lip turns down and out of the way, inasmuch as it is operated by the means which operates the cam 56. At the same time the cam 56 moves from beneath the cam 55 permitting the roll to move downward, the front gages 28 thus following the movement of the turning lip. This is done in order to permit the grippers to pass as close to the surface of the platen as possible, and to allow stiff paper to bend into proper position after the grippers have seized it. After the sheet has been seized by the grippers and has traveled to the platen the turning lip and the cam 56 again move upward, thus restoring the front gages to their normal position.

The gripping mechanism illustrated in Figs. 2, 3, 4, 5 and 6, will now be described. On a gripper rock shaft, 67, are mounted grippers 68, which set against a gripper bar 69, provided with cut out portions 70, for the delivery grippers. The gripper rock shaft and bar are mounted between two carriages 71, which are pivoted at 72 to a collar 73, (Fig. 6), fast on reciprocating rods 74 one on either side of the machine. The said rods travel in suitable bearings 75, on the side frame, and motion is imparted to them by means of a bell crank 76 (Fig. 2), pivoted on the frame at 77, and connected to the said rods by means of a link 78. A spring 79 pushes on the short arm of the said bell crank, and tends to move the guide rods and the gripper mechanism carried thereon downwardly. A further means for effecting this downward motion is found in a rod 80, pivoted on the bed at 81, and pulling against a projection 82 on the bell crank 76. This pull is made yielding by means of a spring 83. The upward motion of the guide rod and gripping mechanism is caused by the rocking of the bed, which pushes the short arm of the bell crank 76 down, hence moving the guide rods up. In order to prevent jars or blows by the engagement of the bed with the said bell crank, the latter is provided with friction rolls 84 (only one of which is seen). The inking mechanism is mounted upon a carrier to which is secured a cam 85, said cam moving in unison with the carrier. As the bed rocks away from the platen, the

cam 85 engages one of the rollers 84 in a smooth and easy fashion, thus starting the downward motion of the bell crank. Next a hub 86 on the bed engages the other roll 84, before the cam 85 leaves the first roll 70 in order to rock the bell crank positively and move the grippers up, but this engagement of the hub with the bell crank takes place without any blow inasmuch as the bell crank has been started on its motion 75 by the cam 85. The operation of these parts is clearly shown in Figs. 2 and 3.

The gripper mechanism travels in a straight line up and down over the surface of the platen 87, and in its travel its pivotal motion is controlled by means of friction rolls 88, on the carriage 71, running on a movable track 89 which is pivoted on the frame at 90. The said track is provided with rolls 91, which are in engagement with cams 92 on a shaft 93. When these rolls are on the high part of the cams, the track 89 is parallel with the surface of the platen, hence the gripper mechanism travels in a line parallel thereto. When the gripper 90 mechanism is at the top of the platen, the grippers are opened by means of a cam 94 (Fig. 3), acting upon a cam roll 95 (Figs. 5 and 6) mounted upon the gripper shaft 67. Furthermore, in this position, the carriage 71 has turned on its pivots 72 by reason of the rolls 88 now running on the high parts 96 of the track, thus bringing the gripper mechanism into the position shown in Fig. 2, where it is ready to seize 100 the sheet.

The cam 94 is mounted upon a vertically reciprocating rod 97, which is pivoted on a lever 98 (Figs. 2 and 3), conveniently mounted in the frame, and which carries a cam roll 99 in engagement with a cam 100, mounted on the shaft 14. From the position shown in Fig. 2, the cam 94 will drop, allowing the grippers to close and seize the edge of the sheet, and as the guide rods are 110 moved down, the carriage will turn on its pivot 72, the guiding roll 88 running on the straight part of the track 89. The said roll is kept in constant engagement with the track by means of a spring 101, which tends 115 to push an arm 102 of the carriage upwardly.

In descending to printing position shown in Figs. 3 and 6 from that shown in Fig. 2, a roll 103 carried by the guide rods comes 120 into engagement with the high part of a cam 104 mounted adjacent to the cam 92, which slackens the speed of the grippers. As the descending motion is continued, this roll continues to keep in engagement with the cam, until the printing position is reached. The track 89 now recedes to allow the grippers to turn in out of the way of the bed, by reason of roll 91 coming on the concentric portion of the cam 92. At this 130

time the roll 88 enters recesses 107 in the track which add to the motion produced by the cam 92. The descending motion of the gripper rod is stopped by reason of the roll 103 coming on the concentric part of the cam 104, while the sheet is being printed. When the printing of the sheet is finished a cam 105 mounted on the rod 97 moves up, thus bringing a straight part 106 of the cam in contact with the gripper rolls 95, whereby the grippers are opened and the sheet is released ready to be removed from the platen by means of the delivery gripper. The grippers move out of the way to allow for this by reason of the roll 103 running into a recess in the cam 104, the track remaining stationary. The gripping mechanism is now ready to travel up to seize the next sheet, and while doing so, the roll 91 again runs on the high part of the cam 92, thus bringing the track into its former position, while the cam 104 moves around and gets ready to receive the roll 103, when the gripper mechanism next moves down. The cam aids in starting the gripper on the upward motion, and thus a very smooth and easy action of the gripper mechanism is assured.

Motion is transmitted to the shaft 93 by any desired means, as beveled gears 108, 109, 110 and 111, shown in Fig. 4. The shaft 112 is suitably supported in brackets 113, 114, shown in Fig. 1, and the shaft 93 is supported in brackets 115. The grippers are normally kept closed by means of a spring 116, shown to the left of Fig. 4.

Suitable means for turning the platen upwardly are provided, and as illustrated, take the following form. On the platen shaft 162, is a worm gear 163, which meshes with a worm 164, upon whose shaft is a hand wheel 165, (Fig. 1). By turning the hand wheel 165 the platen may be moved upwardly and also held firmly in the position shown.

Motion is applied to shaft 22 by any means as a train of gears including a gear 166, pinion 167, gear 168 and intermediate gear 169 meshing with the large gear 3. The pinion 167 carries a crank 167^a (Fig. 7) which connects by means of a rod 170 with the feed table 170^a, for transmitting motion to the same.

While I have illustrated and described a preferred form in which my invention may be embodied, and while I have shown it as it may be constructed when used in connection with a particular type of printing machine, I am aware that many modifications may be made therein, and that the invention can be adapted for use with other types of printing machines by any person skilled in the art without departing from the scope of the invention as expressed in the claims. Therefore, I do not wish to be

limited to the particular construction shown and described, but

What I do claim is:

1. In a printing machine, the combination of a rock-shaft, front gages thereon, a cam for rocking said shaft, and a turning lip rigidly connected to said cam and movable therewith, said turning lip having projections for supporting the front gages. 70

2. In a printing machine, the combination of a rock-shaft, front gages thereon spaced apart, a cam for rocking said shaft, a turning lip on said cam having projections registering with said gages, a gripping device operating between said projections, and means for rocking the turning lip down when the gripping device approaches the sheet held thereon. 75 80

3. In a printing machine, the combination of front gages spaced apart, a turning lip having projections registering with said gages, a gripping device operating between said projections, and means for rocking the turning lip down when the gripping device approaches a sheet held thereon, for 90 95 rocking the lip back after the sheet has been seized by the gripping device, and a cam rigidly connected to said turning lip to move therewith, said cam being effective to lift the front gages to normal position. 95

4. In a gripping device for printing machines, the combination of a pair of rods longitudinally movable in bearings in the frame of the machine, means for longitudinally reciprocating said rods, a carriage 100 pivotally supported on each rod, a gripper bar fixed to said carriages, a rock shaft mounted between said carriages, a set of grippers mounted on said rock shaft and cooperating with said gripper bar, means 105 for opening and closing said grippers, and means for swinging said carriages on their pivots thus positioning the grippers to seize a sheet.

5. In a printing machine, the combination of a bed operating mechanism, a bell-crank adapted to be operated thereby, a sliding bar, means connected with said bell-crank for reciprocating said bar, a carriage 110 115 movably mounted on the bar, and a gripper device mounted on said carriage.

6. In a printing machine, the combination of a bed operating mechanism, a bell-crank adapted to be operated thereby, a sliding bar, means connected with said bell-crank 120 for reciprocating said bar, a carriage movably mounted on the bar, a gripping device mounted on said carriage, and resilient means for forcing said bell-crank in such direction as to withdraw the grippers from 125 operative position.

7. In a printing machine, the combination of a bed-operating mechanism, a bell-crank adapted to be operated thereby, a sliding bar, means connected with said bell-crank 130

4
for reciprocating said bar, a carriage movably mounted on the bar, a gripper device mounted on said carriage, a spring mounted between said bell-crank and the frame for forcing said bell-crank into such position as to withdraw the grippers from sheet receiving position, and a rod pivotally mounted on the bed operating means and resiliently connected with said bell-crank, said

10 rod constituting additional means for normally moving the bell-crank in the same direction.

8. In a printing machine, the combination of bed-operating means, a lever pivotally mounted on a stationary part of the frame, a gripping device, means connected with the lever for moving the gripping device toward and from sheet receiving position, a spring connected with the frame for acting

15 on the lever to withdraw the gripping device from said position, and additional means mounted on the bed operating means and connected with the lever for moving the lever in the same direction.

20 9. In a printing machine, the combination of bed-operating means, a lever, a gripping device, means connected with the lever for operating the gripping device, a carrier for the inking mechanism, and a cam on the bed-operating means movable with said carrier and adapted to engage the lever as the bed moves away from the platen to start the grippers into operative position.

25 10. In a printing machine, the combination of bed-operating means, a lever, a gripping device, a carrier for the inking mechanism, means connected with the lever for operating the gripping device, a cam on the bed-operating means movable with said carrier and adapted to engage the lever as the bed moves away from the platen to start the grippers into operative position in a smooth and easy manner, and a hub on the bed operating means for thereafter engaging

30 40 45 the lever and positively rocking the same to force the gripping device into operative position.

11. In a printing machine, the combination of a gripping device, a movable element for operating the gripping device, a movable bed, a carrier for the inking mechanism mounted thereon, a cam moving with said carrier for engaging said element for operating the gripping device in an easy and smooth manner during the motion of the bed, and means on the bed for thereafter positively moving the said element during the further motion of the bed to force the gripping devices into operative position.

55 60 65 12. In a printing machine the combination of a movable bed, a cam movable on the bed, a gripping device, means connected with the gripping device for receiving initial motion from said cam whereby the gripping device is started by the motion of

the cam and means on the bed for completing the motion of the gripping device after the cam ceases to act thereon.

13. In a printing machine, in combination, a frame, a platen, a movable bed 70 mounted on said frame, a sheet gripping device, connections from said bed to said device for yieldingly operating said device as the bed moves toward the platen, and additional operating means mounted on the 75 frame for yieldingly assisting said movement of the gripping device.

14. In a printing machine the combination of a movable bed, a movable gripping device, means on the bed operating the 80 gripping device, a spring for yieldingly retracting the gripping device and a rod pivotally mounted on the bed and yieldingly connected with the gripping device.

15. In a printing machine, the combination of bed-operating mechanism, a sliding rod, means connected with said mechanism for reciprocating said rod, a gripper mechanism connected with the rod and comprising a carriage movable with respect to the 90 rod and means for holding the carriage in parallel position with respect to the rod during its stroke, and for moving the carriage out of such position to operative position at the end of its stroke.

95 16. In a printing machine, the combination of a reciprocating rod, a carriage movably mounted thereon, a gripper bar on said carriage, grippers movably mounted on the carriage, means for moving the carriage 100 into position parallel with respect to said rod, means for moving the carriage out of such position into sheet receiving position at the end of the stroke, and means for moving the grippers away from the gripper bar.

105 17. In a printing machine, the combination of a reciprocating rod, a carriage pivotally mounted thereon, a gripper bar on the carriage, grippers pivotally mounted on the carriage, means for moving the rod 110 longitudinally upward, means for partially rotating the carriage on its pivot at the upper limit of the travel of the rod, and means for swinging the grippers away from the gripper bar while the carriage is moving on 115 its pivots.

18. In a printing machine, the combination of a reciprocating rod, a carriage pivotally mounted thereon, a gripper bar on the carriage, grippers pivotally mounted on 120 the carriage, means for moving the carriage on its pivot at the end of said upward movement, and means for swinging the grippers away from the gripper bar while the carriage is moving on its pivots, the means for 125 moving the carriage on its pivots comprising a movable track for engaging the carriage.

19. In a printing machine, the combination of a reciprocating rod, a carriage piv- 130

- totally mounted thereon, a gripper bar on the carriage, grippers pivotally mounted on the carriage, means for moving the carriage and the rod to sheet receiving position, 5 means for moving the carriage on its pivots when it reaches said position, and means for swinging the grippers away from the gripper bar while the carriage is moving on its pivots, the means for moving said carriage 10 on its pivots comprising a track pivotally secured to the frame of the machine and having a raised portion at one end and a depressed portion at the other end for engaging a projection on said carriage.
- 15 20. In a printing machine, the combination of a pair of longitudinally movable members, a carriage pivotally mounted on said members, a gripping device carried by the carriage, a cam track pivoted adjacent 20 to the path of movement of said members, means coöperating with said track to swing said carriage relative to said members, and additional means to move said track about its pivot.
- 25 21. In a printing machine, the combination of a longitudinally movable carriage, means for swinging said carriage at the end of its stroke, grippers pivotally mounted on the carriage, a cam for operating said 30 grippers, a longitudinally movable rod on which said cam is fixed, a lever connected to move said rod longitudinally, and a cam for operating said lever.
22. In a printing machine, the combination 35 of a carriage pivoted upon a movable support, means for reciprocating said support, a gripping mechanism mounted on said carriage, means for opening the grippers at the upper end of the travel of the support, 40 means for turning the carriage and grippers relatively to the support at the upper end of the travel into position to receive a fresh sheet, and means for thereafter closing the grippers.
- 45 23. In a printing machine, the combination 50 of a reciprocable carriage, a gripping mechanism mounted on said carriage, and comprising movable grippers, means for opening the grippers, means for moving the carriage and grippers into position for taking a sheet, means for thereafter allowing the grippers to close and seize a sheet, means for then withdrawing the carriage, a cam having an eccentric portion for slackening 55 the motion of the carriage before it reaches the end of its stroke, and a low surface for permitting the carriage to move to the end of its stroke, and means for printing on a sheet held by the gripping device.
- 50 24. In a printing machine, the combination 60 of a carriage, a gripping mechanism mounted thereon, means for reciprocating said carriage, and a cam adapted to move in the path of a portion of said carriage and slacken the motion of the carriage before it reaches the end of the stroke, and hold it in position for printing on a sheet held by the gripping device.
25. In a printing machine, the combination 70 of a support, a carriage mounted to reciprocate with said support, a gripping mechanism mounted thereon, means for reciprocating the carriage and its support, and means for slackening the motion of the carriage on its delivery stroke and for thereafter permitting the carriage to complete 75 the delivery stroke.
26. In a printing machine, the combination 80 of a reciprocating carriage having a gripping device thereon, means for reciprocating the carriage, and a cam adapted to engage the carriage toward the end of its stroke and slacken its motion, then permit the carriage to complete its stroke, and finally to start the carriage on its return 85 stroke.
27. In a printing machine, the combination 90 of a carriage, means for reciprocating said carriage, a gripping mechanism mounted on said carriage, and comprising movable grippers, means for opening the grippers at the end of the stroke of the carriage, means for moving the carriage and grippers into position for taking a sheet, means for thereafter allowing the grippers to close and 95 seize a sheet, means for then withdrawing the carriage, a cam having an eccentric portion for slackening the motion of the carriage before it reaches the end of its stroke, and a low surface for permitting the carriage to move to the end of its stroke, means for printing on a sheet held by the gripping device, and means for thereafter retracting 100 the grippers and releasing the sheet.
28. In a printing machine, in combination 105 with members movable longitudinally in a straight line, a carriage pivotally mounted on said members and movable therewith, and a rail for guiding said carriage, said rail having a straight portion for guiding the carriage to move in a position parallel with respect to said members during the main portion of its stroke and having a recess for permitting the carriage to move backward with respect to said member at 115 the lower end of its stroke.
29. In a printing machine, the combination 120 of a carriage, a gripping device mounted on said carriage, means for reciprocating the carriage, said carriage being pivotally mounted, a movable cam rail extending adjacent the path of reciprocation of said carriage for controlling the motion of the carriage about its pivot, and means for swinging said rail backward at the lower 125 end of the stroke of the carriage.
30. In a printing machine, in combination 130 with a movable bed, a pivoted reciprocating carriage, a cam rail, a gripper device on the carriage, and a movable member for con- 135

trolling the position of the rail and permitting its retraction near the lower end of the travel of the carriage to swing the gripper device out of the way of the bed, said rail having a recess to permit more rapid retraction of the carriage.

In testimony whereof I have hereunto set

my hand, in the presence of two subscribing witnesses.

THOMAS C. SHEEHAN.
